Primary Examiner — Vy N Koenig(74) *Attorney, Agent, or Firm* — Frank Gao, Esq.(57) **CLAIM**

The ornamental design for a safety vest, as shown and described.

DESCRIPTION

FIG. 1 is a front elevation view of a safety vest showing my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a front, top, left perspective view thereof; and,

FIG. 8 is a rear, top, right perspective view thereof.

The portions depicted in broken dashed lines of even length are included for the purpose of illustrating environmental structure and form no part of the claimed design.
